Application December 30, 1954, Serial No. 478,651

15 Claims. (Cl. 101—93)

This invention relates to wire printers and more particularly to wire printers wherein the print wires, to form a character pattern on a matrix containing their print ends, are preset so that they may undergo yielding displacement during printing impact to create characters whose component dots are of uniform impression.

It is heretofore been proposed (United States patent application No. 255,391, particularly Fig. 7, of Reynold B. Johnson, filed November 8, 1951, and issued as Patent No. 2,730,040 on January 10, 1956) to preset print wires by means of a milled code rod operating upon the equally spaced, parallelly extending, and aligned control ends of print wires. Such a rod is formed with high and low portions so that when one of the code rod and aligned control ends is moved against the other, those wires which are abutted by high portions are displaced longitudinally relative to those which are received in the low portions or notches. In a milled code rod, notches are provided on each of four sides of an otherwise solid rod. The diameter and the spacing of the print wires is such that a number of high and/or low portions occur on each of the four sides of the code rod between adjacent print wires. Thus, it can be seen that, by providing for rotation of the code rod so that any of its four sides can be presented to the print wire control ends and also for its translation so that any of the successive high and/or low portions for each print wire control end can be aligned therewith for movement thereagainst, the selection of a large number of different character patterns may be readily effected; the maximum number being equal to the product of the number of high and/or low portions for each print wire control end and the number of code rod sides. In the embodiments disclosed in the above identified application, this number would total forty-eight, as provision was made for twelve axial positions on each of four radial spaced code rod positions.

The construction of a milled code rod is a difficult and time-consuming and, hence, costly operation. In forming the transverse cuts in such a rod, considerable heat is developed with the result that the rod undergoes expansion. Thus, not only must the cuts be made at low speed, but some time must be allowed to elapse between cuts to allow for cooling off of the rod so that the new cuts may be accurately located. But the wastage of time is not the only disadvantage; the repeated heating and cooling of the rod reduces its temper so that it must be heat-treated again. It is the necessity for this heat treatment that renders the construction of a milled code rod onerous, for it is extremely difficult to heat-treat such a rod and yet maintain dimensional stability. In other words, a heat treatment tends to render the milled rod inaccurate.

Then, too, in more recent wire printer developments, speed has been a prime consideration. In the design of high-speed machines, however, it is desirable that the moving parts be formed of low mass inasmuch as this provides for low inertia with attendant light energy expenditures, reduced wear and tear, and quietness of operation. One way of obtaining low mass is by reducing the size of the various moving parts. Normally, this is not attended to without difficulties, particularly as concerns strength, which usually is proportional to the amount

2

of material employed. A milled code rod has other limitations in this respect, as it is almost impossible to reduce the size of the code rod to a desired degree without sacrificing the differential displacement between the set and preset wires, as the milled rod cannot be cut even to the center line of the rod. In other words, a milled code rod must have a minimum diameter in order to provide the desired displacement and to provide the necessary rigidity of construction.

Accordingly, a main object of the invention is to provide a code rod which is easy and inexpensive of construction.

Another object of this invention is to provide a code rod or wire setting device which can be advantageously utilized in high-speed printers.

A more specific object of the invention is to provide a code rod having the desired properties of low mass but yet high strength.

Another object of the invention is to provide such a code rod which provides the desired relative displacement between the preset and non-set print wires.

According to the invention the wire setting device or code rod is formed as a perforated hollow cylindrical rod or tube of steel or like material. The rod is radially perforated at those points which, for a given shifted position of the device, are aligned with the control ends of those print wires which form no part of the corresponding desired character pattern, just as the code rod is milled at similar points. However, in contrast with the milled code rod, the maximum amount of differential displacement which can be imparted to the preset and non-set print wires is determined by the sum of the interior diameter and the thickness of the wall of the tube, as the preset print wires could be moved this distance before the non-set print wires engaged the interior surface of the code rod wall opposite that facing the print wire control ends.

A wire setting device constructed as a perforated hollow rod combines the desired qualities of low mass and high strength, for the elimination of the center portion of a rod eliminates much of the mass without a commensurate reduction in the strength and stability. Moreover, the making of perforations instead of transverse cuts in a rod removes much less material from the periphery of the rod and hence results in a stronger and more rigid wire setting device.

A perforated hollow code rod or tube is also easy and inexpensive of construction. Almost any standard tubular steel stock may be employed as no close tolerances are required, except to some extent in the external diameter.

The formation of the perforations in the tube is a simple matter of drilling the tubes at the proper points, as, for example, by a template controlled pantograph machine. The wire printer requirement that the means for imparting translation and rotation to a code rod be fixed in a machine, and hence non-movable with the code rod in its displacements toward and away from the print wire control ends, may be readily complied with as by reducing, by drawing, for example, one end of the control rod and sweating it on one end of a flexible stem having its other end associated with the rotation and translation imparting means.

A further feature of the invention is that the control ends of the print wires operated by the code rod may be spaced closer together than heretofore, with the result that wire printers of more compact design are obtained. The print wire control ends may be spaced closer together because a code rod constructed according to the instant invention may be shorter. This is so for two reasons. One is that the use of perforations enables the control points to be spaced closer in the radial di-

rection because the making of perforations removes much less surface material from a rod than milling operations. In the instant embodiment a code rod having seven different and equally spaced sides is provided instead of one having the conventional four. Since the number of character patterns which may be formed is, within the limits defined by the number of print wires employed, equal to the product of the radial and axial positions in which the code rod may be disposed, it follows that by increasing the number of radial positions, the number of axial positions and hence the length of the code rod may be reduced without affecting the number of character patterns which can be selected.

The other reason is that the use of perforations which are circular enables the control points also to be spaced closer in the axial direction. Less material must be left between low portions or perforations to form a high portion or land, as no long thin wall of material between cuts is involved; rather, the material to either side of a center line connecting adjacent perforations rapidly fans out to form a broad or reinforcing base for the very small amount of material constituting a high point or land between perforations. Moreover, adjacent low portions or perforations may overlap. Evidently, then, if the control points may be located closer to each other, the code rod can be further shortened.

Other objects of the invention will be pointed out in the following description and claims and illustrated in the accompanying drawings, which disclose, by way of example, the principle of the invention and the best mode which has been contemplated of applying that principle.

In the drawings:

Fig. 1 is a vertical view partly in section of structures embodying a code rod constructed according to the instant invention.

Fig. 2 is an enlarged view, partly in section, of a portion of the apparatus shown in Fig. 1.

Fig. 3 is a view taken along the section line 3—3 of Fig. 2.

Referring more particularly to Fig. 1, a typical high-speed printer environment for the code rod constructed according to the invention is shown. In high-speed wire printers, wherein movable parts preferably are formed of low mass and yet high strength, a code rod 10 is shown as being slidably mounted in a carrier tube 12. This carrier tube is mounted in a housing or bail which guides the control ends 14a of a plurality of print wires 14 and is reciprocable in the direction of these control ends to move the code rod, which would already have been shifted to a particular position if printing is to occur, against the print wire control ends to effect a differential displacement thereof.

The housing or bail is formed of two parts, a back plate 16 and a front plate 18 which is rigidly secured together in any suitable manner. The back plate 16 is formed along its right-hand edge with a number of lateral extensions or lugs 16a each having an aligned vertically extending groove; and in these grooves is seated the carrier tube, the depth of the grooves being such as to accommodate substantially half of the tube. The back plate is also formed with a plurality of horizontally extending grooves on the side facing the front plate; and these grooves are of such size as to slidably accommodate the respective print wire control ends 14a. The front plate 18 is provided with a number of extensions 18a which encompass the tube 12 and hold it in the vertically aligned grooves in the lugs 16a. When the housing or bail is moved in the direction of the print wire control ends, the control ends remain in place with the housing moving relative to them.

The housing or bail itself may be supported for sliding movement by means of lower and upper guides 20 and 22 suitably fixed in the machine. A pair of springs 24 act upon the housing at all times to urge it in the direction away from the print wire control ends. The position of

the housing is at all times determined by operating elements, such as the parts 26, which act upon corresponding lugs 16a of the back plate 16.

The operating elements 26, which may be slidably supported in guides 25, have a normal position which may be determined through abutting relationship with corresponding synchronously operated cams 27, and the springs 24 cause the housing to be positioned in a normal position according to the location of the operating elements 26. In this normal position of the housing, the code rod 10 is free and clear of the print wire control ends 14a and thus may be shifted to any desired position. When the operating elements 26 are displaced from the normal position by the rotating cams 27, they move the housing against the print wire control ends, which remain in place as they are slidably accommodated within the channels formed in the front plate 18 engaging surface of the back plate 16. This movement of the housing will be sufficient to bring the print wire control ends into the carrier tube through openings 30 formed therein opposite the respective print wires. Movement of the housing continues so that those print wires which are aligned with a perforation 32 in the code rod 10 enter the code rod therethrough for a considerable distance, as may be best seen by the dotted line position of the code rod and carrier tube in Fig. 3. On the other hand, those print wire control ends which do not find themselves aligned with a perforation but rather with a land in the code rod will be displaced longitudinally of the remainder of such print wires by the distance that the non-selected print wires enter the code rod, as shown in Fig. 3.

As best seen in Figs. 2 and 3, the code rod is formed of seven evenly spaced columns, numbered H, 1, 2, 3, 4, 5, and 6 (Fig. 3), of variously spaced perforations 32. The code rod perforations 32, each of a size sufficient to readily accommodate a corresponding print wire control end 14a, are small compared to the distance between adjacent print wires, so that a number, actually 8, may be located in each column for each print wire. Since the code rod can be rotated to any of seven radially spaced positions and translated to any of eight axially spaced positions, it follows that fifty-six different combinations of print wire displacements or character patterns may be effected. Conveniently, a home position, having a perforation for each print wire control end 14a, is provided for the code rod, which entails zero radial displacement from the normal position as well as zero axial displacement from the normal position. In this way, if no signal or signals representative of a particular character exist, in which case no axial and/or radial displacement would be imparted to the code rod, no differential displacement would be imparted to any of the print wires 14, and hence no character pattern would be created on a print wire matrix which could result in a character impression during the subsequent printing stroke.

The home position of the code rod in the axial direction occurs at the upper end of its range of movement—in other words, the code rod is displaced downward in order to introduce character patterns other than those which can be obtained by merely rotating the code rod to any of its other seven, that is, 1 through 7, positions. The code rod is biased upwardly to this position by a spring 34 which is swiveledly corrected to the upper end of the code rod 10 so that the latter may rotate, at least to some extent, independently of the former.

The shifting of the code rod to its various positions is accomplished through a flexible stem 36, to the upper end of which the lower drawn end of the code rod is attached. The lower end of the stem is provided with an elongated gear 35 to which rotation may be imparted by a rack or racks 40. Axial displacement of the code rod is imparted thereto by a bifurcated lever 44 through the stem by a thrust washer 42 mounted on the stem, so as to rest upon the upper end of the gear 35. The length and flexibility of the stem 36 is such that the move-

ment of the code rod toward and away from the print wire control ends 14a may be readily accomplished without requiring movement of the rotation and translation movement imparting elements 40 and 44 and otherwise effecting the differential position to which the code rod 10 has been shifted.

Once the code rod has been positioned, it may be moved against the print wire control ends by the operation of the elements 26 as heretofore described to impart a differential setting on the print wires 14. The printing stroke, however, does not take place until the housing has returned a considerable distance to its original position as the print wires undergo substantial longitudinal displacement upon impact. They will not, however, be fully restored by the printing impact, and to this end the left-hand edge of the back plate 16 is cut away and bent forwardly to form flanges 46 which engage the headed end of the collars 48 affixed to the print wires. This engagement of the headed collars 48 by the flanges 46 occurs during the final portion of the movement of the housing to its normal position, and it results that when the housing is fully restored, all of the displaced print wire control ends will also have been fully restored to an aligned condition.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a high-speed wire printer embodying moving parts of low mass but yet high strength; a plurality of print wires having control ends; and a device for differentially displacing the print wires disposed opposite the control ends and comprising a hollow body, and perforations, of a size sufficient to accommodate the free passage of print wires, formed in said body; means for adjusting the disposition of the hollow body relative to the control ends; and means for thereafter bodily moving one of said control ends and said adjusted hollow body into engagement with the other to displace the print wires aligned with non-perforated portions of the hollow body longitudinally with respect to those entering perforations.

2. In a high-speed wire printer embodying moving parts of low mass but yet high strength; a plurality of print wires having control ends parallelly extending, aligned, and equally spaced; and a device adapted to be moved against the control ends of the print wires comprising a hollow generally cylindrical body, and radially extending perforations, of a size sufficient to accommodate the free passage of print wire control ends, formed in said body; means for adjusting the disposition of the cylindrical body relative to the control ends; and means for thereafter bodily moving one of said control ends and said cylindrical body into engagement with the other to displace the print wires aligned with non-perforated portions of the cylindrical body longitudinally with respect to those entering perforations.

3. In a high-speed wire printer embodying moving parts of low mass but yet high strength; a plurality of print wires having control ends; a device for operating on the control ends of the print wires to differentially displace them comprising a hollow body adapted to be shifted to various positions opposite said print wire control ends, and perforations, of a size sufficient to accommodate the free passage of wires, formed in and about said body so that various ones thereof are aligned with various ones of said control ends when the body has been shifted to its different positions; means for shifting the hollow body to various positions opposite said

control ends; and means for thereafter bodily moving one of said control ends and said hollow body into engagement with the other to displace the print wires aligned with non-perforated portions of the hollow body longitudinally with respect to those entering perforations.

4. In a high-speed wire printer embodying moving parts of low mass but yet high strength; a plurality of print wires having control ends; and a device for operating on the control ends of the print wires comprising a hollow body, and perforations, of a size sufficient to accommodate the free passage of wires, formed in and about said body so that movement of the device to different positions opposite said print wire control ends will dispose different perforations opposite various ones of the print wires; means for moving the device to different positions opposite the print wire control ends; and means for thereafter bodily moving one of said control ends and said device into engagement with the other to displace the print wires aligned with non-perforated portions of the hollow body longitudinally with respect to those entering perforations.

5. In a high-speed wire printer embodying moving parts of low mass but yet high strength; a plurality of spaced print wires; a device for differentially setting said spaced print wires comprising a tubular body adapted to have a home position and be shiftable to other positions opposite said print wires, perforations formed in said tubular body adapted to be aligned with the respective ones of said print wires when said body is in the home position, and other perforations formed in said body and adapted to be aligned with various ones of said print wires when said body is in its other positions; means for shifting said tubular body to other positions opposite said print wires; and means for thereafter bodily moving one of said control ends and said tubular body into engagement with the other to displace the print wires aligned with the non-perforated portions of the tubular body longitudinally with respect to those entering perforations.

40 6. In a high-speed wire printer embodying moving parts of low mass but yet high strength; a plurality of print wires having control ends; and a device for operating upon the control ends of the print wires comprising a tubular body adapted to be shifted to various positions opposite the control ends of said print wires, and perforations formed in said body and adapted to be aligned with various ones of said control ends when said body has been shifted to different positions; means for shifting the tubular body to various positions opposite the control ends; and means for thereafter bodily moving one of said control ends and said tubular body into engagement with the other to displace the print wires aligned with non-perforated portions of the tubular body longitudinally with respect to those entering perforations.

55 7. In a high-speed wire printer embodying moving parts of low mass but yet high strength; a plurality of print wires having control ends; a device for operating upon the control ends of the print wires comprising a tubular body adapted to have a home position and be rotated and translated to other positions opposite the control ends of said print wires, perforations formed in said body so as to be aligned with the respective control ends when said body is in the home position, and other perforations formed in said body and adapted to be aligned with various ones of said control ends when said body has been rotated and translated to a corresponding one of its other positions; means for rotating and translating the tubular body to other positions opposite the control ends of said print wires; and means for thereafter bodily moving said tubular body against the control ends of the print wires so that the control ends aligned with non-perforated portions of the tubular body are longitudinally displaced with respect to those control ends entering perforations.

8. In a high-speed wire printer embodying moving

parts of low mass but yet high strength; a plurality of print wires having control ends; and a device movable against the control ends of the print wires to displace various ones thereof comprising a tubular body, and radially and axially spaced perforations of a size sufficient to accommodate the free passage of print wires formed in said tubular body; means for adjusting the disposition of the tubular body relative to the control ends; and means for thereafter bodily moving one of said control ends and said adjusted tubular body into engagement with the other to displace the print wires aligned with non-perforated portions of the tubular body longitudinally with respect to those entering perforations.

9. In a high-speed wire printer embodying moving parts of low mass but yet high strength; a plurality of print wires having equally spaced control ends; and a device movable against the equally spaced control ends of the print wires to displace various ones thereof comprising a tubular body adapted to have a home position and be rotated and translated to other positions opposite said print wires, and radially and axially spaced perforations for the respective control ends formed in said tubular body and adapted to be successively aligned therewith when the tubular body is rotated or translated; means for rotating and translating the tubular body to other positions opposite said print wire control ends; and means for thereafter bodily moving said tubular body against the control ends so that the print wires aligned with non-perforated portions of the tubular body are longitudinally displaced with respect to those entering perforations.

10. In a high-speed wire printer embodying moving parts of low mass but yet high strength, a plurality of print wires having equally spaced control ends, and a device for operating upon the equally spaced control ends of the print wires comprising a tubular body adapted to be rotated and translated to various positions opposite said print wire control ends and radially and axially spaced perforations for the respective control ends formed in said body and adapted to be successively aligned therewith when the tubular body is rotated or translated, means for rotating and translating the tubular body to various positions opposite said print wire control ends, and means for thereafter bodily moving said tubular body against the control ends so that the print wires aligned with non-perforated portions of the tubular body are longitudinally displaced with respect to those entering perforations.

11. For use in a high-speed wire printer embodying moving parts of low mass but yet high strength, a plurality of print wires having control ends, a device for differentially setting print wires comprising a tubular body adapted to be moved to different positions opposite said print wire control ends, a stem fixed to one end of said tubular body to transmit rotation and translation to said body to move it to its different positions, perforations formed in said body and adapted to be aligned with different ones of said print wire control ends when the tubular body is in its various positions, means for imparting rotation and translation to said stem for transmission to said tubular body to move the latter to its different positions, and means for thereafter bodily moving said tubular body against the control ends so that the print wires aligned with non-perforated portions of the tubular body are longitudinally displaced with respect to those entering perforations.

12. For use in a high-speed wire printer embodying moving parts of low mass but yet high strength, a device movable against the control ends of print wires to differentially displace them comprising a hollow body adapted to be shifted to various positions opposite said print wire control ends and thereafter moved thereagainst, perforations of a size sufficient to accommodate the free passage of print wires formed in said body so as to be aligned with various ones of said control ends when said

body has been shifted to a corresponding one of its various positions, a stem secured at one end to one end of said tubular body, and means for imparting rotation and translation to said stem to move the tubular body to its various positions fixed to the other end of said stem, said stem being of such length and flexibility as to accommodate movement of the tubular member against said print wire control ends without requiring movement of the means for imparting rotation and translation to it and the body.

13. For use in a high-speed wire printer embodying moving parts of low mass but yet high strength, a device movable against the control ends of print wires to differentially displace them comprising a tubular body adapted to have a home position and be shifted to other positions prior to being moved against the print wire control ends, perforations formed in said body so as to be aligned with the respective print wire control ends when said body is in the home position, other perforations formed in said body and adapted to be aligned with various ones of said print wire control ends when the body is in a corresponding one of its other positions, a flexible stem fixed at one end to one end of said tubular body, a gear fixed to the other end of said stem for imparting rotation thereto to shift the tubular body, a collet fixed to said stem to enable translation of said body from its home position, and means associated with said tubular body and stem for biasing them so that the collet is held in engagement with an operating element therefor.

14. For use in a high-speed wire printer embodying moving parts of low mass but yet high strength, a device adapted to be moved against the control ends of print wires to differentially displace them comprising a tubular body adapted to be shifted to various positions opposite said print wire control ends, and perforations of a size sufficient to accommodate the free passage of print wires formed in and about said body so that various ones thereof are aligned with various ones of said control ends when the body is in its different positions; a carrier tube for moving said tubular body in its different positions against said print wire control ends; and perforations formed in said carrier tube to permit all of the print wires to pass therethrough for displacement by said device.

15. For use in a high-speed wire printer embodying moving parts of low mass but yet high strength, a device adapted to be moved against the equally spaced control ends of print wires to differentially displace them comprising a tubular body adapted to have a home position and to be shifted to various other positions opposite said print wire control ends; axially spaced perforations of a size sufficient to accommodate the free passage of print wires formed in said body so as to align with the respective print wires when the body is in home position; and other axially and radially spaced perforations of a size sufficient to accommodate the free passage of print wires formed in said body so that various ones thereof are aligned with various ones of said print wire control ends when said body is in its different positions; a carrier tube for moving said tubular body in its different positions against said print wire control ends; and perforations formed in said carrier tube to permit all of the print wires to pass therethrough for displacement by said device.
